ILLUMINABLE COCKTAIL TABLE

William Orval Webb, 3113 E. 8th St.,
Joplin, Mo. 64801

Filed July 24, 1972, Ser. No. 274,281

Term of patent 7 years

Int. Cl. D6—03
U.S. Cl. D6—177

FIG. 1.

FIG. 2.

FIG. I is a perspective view of the an illuminable cocktail table which is the subject made of the application. The particular ornamental design feature is the combination of glass as shown in cutaway View I said glass has a rippled surface and the rippled surface is located opposite a surface contacting lights as shown by cutaway View 2.

FIG. II is a photography of said an illuminable cocktail table illustrating the geometric diffusion of light caused by the rippled sub-surface of the glass top.

FIG. III is the elevation view of the an illuminable cocktail table which is the subject made also of this application. (See under FIG. I. This is a closer view of Views I and II.)

I claim:

The ornamental design for an illuminable cocktail table, as shown and described.
